(57) **CLAIM**

The ornamental design for a tubular food container, as shown and described.

DESCRIPTION

FIG. 1 is a perspective view of a tubular food container showing our new design;

FIG. 2 is a side elevational view of an outer container body; shown separately for clarity;

FIG. 3 is a bottom plan view of FIG. 2;

FIG. 4 is a top plan view of FIG. 2;

FIG. 5 is a perspective view of an inner support bar; shown separately for clarity;

FIG. 6 is a side elevational view of FIG. 5;

FIG. 7 is a bottom plan view of FIG. 5; and,

FIG. 8 is a top plan view of FIG. 5.

The broken line showing of food chips is for illustrative purpose only and forms no part of the claimed design.
